SHAKER CONVEYER

Loy D. Hagenbook, Chicago, Ill., assignor to
 Goodman Manufacturing Company, Chicago,
 Ill., a corporation of Illinois

Application December 22, 1945, Serial No. 636,730

15 Claims. (Cl. 198—220)

1

This invention relates to improvements in shaker conveyors, and more particularly relates to improvements in articulated connections in shaker conveyor trough lines arranged to permit lateral movement of one trough of the conveyor with respect to another trough of the conveyor, for conveying material around corners.

Considerable difficulty has heretofore been encountered in articulated connections in shaker conveyor trough lines or swivels in that the mine floor is very seldom level and irregularities in the mine floor cause bending of the base of the swivel, which makes it difficult to hold the swivel in position on the ground and causes binding of the articulated troughs and the trough supporting means therefor mounted on the base, with a resultant frequent breakage of parts of the swivel.

The device of my present invention has as its principal object to provide a novel form of holding connection between the holding jacks and the base of a swivel, permitting relative vertical movement between the jacks and base when the jacks are initially set between the mine roof and the ground, and holding the base firmly in position on the ground by forces exerted in planes substantially parallel to the supporting surface of the base of the swivel, when tightening the jacks against the mine roof, and thus avoiding distortion or bending of the swivel base and binding of the moving parts mounted thereon.

This and other objects of my invention will appear from time to time as the following specification proceeds and with reference to the accompanying drawings wherein:

Figure 1 is a plan view of a swivel constructed in accordance with my invention, with certain parts broken away in order to more clearly illustrate certain details of my invention;

Figure 2 is an enlarged fragmentary longitudinal sectional view taken substantially through the longitudinal center of the swivel shown in Figure 1;

Figure 3 is a fragmentary transverse sectional view taken substantially along line 3—3 of Figure 1;

Figure 4 is a transverse sectional view taken substantially along line 4—4 of Figure 1;

Figure 5 is a fragmentary longitudinal sectional view taken substantially along line 5—5 of Figure 1;

Figure 6 is a fragmentary sectional view taken substantially along line 6—6 of Figure 1; and

Figure 7 is a detail sectional view taken substantially along line 7—7 of Figure 3.

In the drawings, the embodiment of my inven-

2

tion illustrated is shown as providing an articulated connection between a driving trough 10 of a shaker conveyor trough line and a forwardly spaced driven trough 11, to permit lateral swinging movement of said driven trough with respect to said driving trough about a plurality of parallel spaced vertical axes, so the conveyor may carry material around corners, or so a pick-up member on the forward end of the driven trough may pick up material from the extreme corners of a wide room, or may be extended along a cross cut or entry at an angle to the main part of the conveyor, to pick up material therefrom.

The articulated connection between the driving 15 and the driven troughs of the conveyor operates on principles somewhat similar to those shown and described in Patent No. 2,330,946, which issued to E. R. Bergmann on October 5, 1943, and includes a base 12 adapted to be held in position 20 on the ground during operation of the conveyor by means of a plurality of jacks 13, 13 in a manner which will hereinafter be more fully described as this specification proceeds.

A relatively short intermediate trough 15 having outwardly flared curved forward and rear ends 16 and 17, respectively, is connected between a connecting trough 19, connected at its receiving end to the driven trough 11, and a connecting trough 20 detachably connected at its discharge end to the driving trough 10 in a well known manner. Said connecting trough 19 has a curved discharge end conforming substantially to the form of the curved forward end 16 of the intermediate trough 15, and is nested within said forward end of said trough so as to discharge material onto said trough when in various positions of articulation with respect thereto. The curved rear end 17 of said intermediate trough is nested within a curved receiving end of the connecting trough 20, which curved end conforms to the form of said curved rear end, to provide a continuous closed trough, when said intermediate trough is in various positions of articulation with respect to said connecting trough.

45 The intermediate trough 15 is pivotally connected adjacent its receiving and discharge ends to said connecting troughs 19 and 20, respectively, by means of bosses 22 and 23, respectively. The boss 22 is mounted in the bottom of the 50 connecting trough 20 and depends therefrom and extends through and has bearing engagement with an annular bearing member 24 secured to and depending from the bottom of the forward end of the intermediate trough 15 (see Figure 2). Said annular bearing member 24 is shown in Fig-

ure 2 as resting on and as being slidably movable across a supporting plate 25 of an outboard support and control member 23, extending forwardly of the base 12 and secured to and forming an outboard support and control member for the forward end of the connecting trough 19. Said outboard support and control member also extends rearwardly from the boss 22 and has a bifurcated rear end portion 27 having slidable guiding engagement with opposite sides of a guide frame 29, mounted for movement about a boss 30 mounted on the forward end of the base 12 and projecting upwardly therefrom. The inner sides of the furcations of the bifurcated portion of said support and control member are provided with inwardly facing channelled guide portions 31, 31 forming a guide and mounting for a pair of facing supporting guides 32, 32. Said guides have V-shaped bearing faces 33, 33 having slidable engagement with corresponding recessed guides 34, 34 extending along opposite sides of said guide frame 29 and forming a guide and support means for the rear end of said outboard support and control member 26 during reciprocal movement of said control member with respect to the base 12.

The guides 32, 32 may be made of a suitable bearing material and the portions thereof mounted within the channelled portions 31, 31 of the furcations of the support and control member 26 are transversely slotted as indicated by reference character 35. Bolts 36, 36 having nuts thereon extend through said slotted portions to hold said guides in position in said channelled portions. Set screws 37, 37 having lock nuts 38, 38 threaded thereon are provided to adjust said guides to take care of wear thereof.

The guide frame 29 is provided with a partial-ball-shaped central recessed portion, the widest portion of which opens towards its top, which has engagement with a partial-ball-shaped bearing member 39, mounted on the upright boss 30, and held in position thereon by means of a washer 40 and a cap screw 41, threaded in said boss and engaging the upper side of said washer. Pivotal movement of said guide frame 29 about the bearing member 39 about axes extending longitudinally of said guide frame is limited by a pair of parallel spaced runners 43, 43 having convex bottom surfaces resting on the top of the base 12, so as to permit movement of said guide frame about an axis transverse to said guide frame, so said guide frame may conform to changes in elevation of the driven trough 11 and the connecting trough 19, but to hold said guide frame from movement about a longitudinal axis (see Figures 2 and 4).

The boss 23 is mounted in the bottom of the intermediate trough 15 adjacent the rear end thereof, and depends therefrom. An annular bearing member 44 is mounted on said boss 23 and is held in position thereon by means of a retaining cap 45 mounted on the bottom of said boss by means of cap screws 46, 46. A guide frame 47 is journaled on said annular bearing member and has opposite facing longitudinally extending V-shaped engaging faces 49, 49 extending therealong, which are adapted to register for slidable engagement with V-shaped guides 50, 50 formed in supporting and guide blocks 51, 51. Each of said supporting and guide blocks is herein shown as having an integrally formed shaft 52 extending outwardly therefrom and transversely pivoted in an adjustable support member 54 mounted on a plate 53, mounted on

and spaced upwardly from the base 12 on ribs 48, 49 extending transversely of said base. Said adjustable support member is engaged at its outer side with a set screw 55 arranged to move said support inwardly as the faces 49, 49 and 50, 50 wear. Said set screw is threaded in an upright flanged portion 56 of the plate 53, and is held in fixed relation with respect thereto by means of a lock nut 57. A plurality of nuts and bolts 59, 59 extending through said adjustable support member and through slotted portions of said plate (not shown) are provided to hold said adjustable support member in position. The pivotal mounting of the support and guide blocks 50, 50 thus affords a transversely pivoted support for the guide frame 47, permitting the connecting trough 20 and the driving trough 10 to adapt themselves to irregularities in the mine bottom.

The jacks 13, 13 are herein shown as being well known forms of screw jacks adapted to be interposed between opposite sides of the base 12 and the mine roof, to hold said base in position on the ground, and may be of any suitable construction. An engaging member 60 is transversely pivoted to the lower end of each of said jacks. Said engaging member has a downwardly extending stud adapted to engage an apertured portion of a hinged bearing plate 61. Said plate is adapted to be moved into engagement with the top of an engaging member 63, upon setting of the respective jack, so as to engage a shoe 64 with the ground and hold said base in position on the ground in a manner which will herein-after more clearly appear as this specification proceeds. Said bearing plate is pivotally mounted on a pin 65 mounted in a member 66 which is mounted in an outer enlarged portion of an annular ring 67, on a depending shaft 68. Said bearing plate besides forming a bearing member for the jack 13, also serves to move a centering stop 69 out of position to be engaged by stops 70, 70 depending from the guide frame 47.

The centering stop 69 is formed on a transversely guided slidable member 71, slidably guided in the plate 53, beneath the guide block 51. Said stop is moved to a position to be engaged by the stops 70, 70, when the jack 13 is released from said plate, and pressure is relieved from the hinged bearing plate 61, by means of a compression spring 72, engaging an abutment plate 73, secured to and depending from the inner end of said slidable member. A link 74 is pivotally connected between said slidable member and a lever arm 75, depending from said hinged plate, and herein shown as being formed integrally therewith, to pivot said plate upwardly by means of said spring 72 when said jack is released from said plate.

The stops 70, 70 are spaced apart a distance equal to the stroke of the conveyor plus the distance between opposite engaging faces of the centering stop 69, and serve to center the base 12 with relation to the stroke of the conveyor before the setting of the jacks 13, 13 on said hinged plates, in a manner which has been shown and described in Patent No. 2,347,074, which issued to E. R. Bergmann on April 18, 1944, and which is no part of my present invention so is not herein described in detail.

The means for holding the base 12 in position on the mine bottom in a plane substantially conforming to the shaker conveyor trough line, where the mine bottom is irregular, without exerting any bending forces on said base, includes the 75 annular ring 67 on each side of said base and

a split or sectional collar 76 adapted to engage each of said rings. Each of said collars is mounted in one of said rings for vertical movement with respect thereto, when initially setting the associated jack 13, and is also adapted to firmly grip said annular ring and hold it and said base from movement, when the base is in the proper relation with respect to the conveyor trough line and the associated jack has been set (see Figures 3 and 7). Said collar is herein shown as being in three sections and has a convex socket opening towards the ground, which is in the form of a portion of a sphere. Said socket is adapted to engage a partial-ball-shaped, upwardly projecting portion 77 of the ground engaging shoe 64, and form a universal pivotal mounting for said shoe. A partial-ball-shaped bearing member 79 is mounted in said shoe for universal pivotal movement with respect thereto, and has an upright sleeve 80 mounted therein and projecting upwardly therefrom, and abutting the engaging member 63. Said engaging member has a frusto-conical engaging face adapted to register with a corresponding face on the inside of said sectional collar, for expanding said collar when said engaging member is moved downwardly by the jack 13. A bolt 81 extends through said sleeve and through said engaging member. A washer 82 abuts the head of said bolt and also abuts the lower end of said sleeve 80 and the bearing member 79, and a nut and lock washer 83 on the opposite end of said bolt serves to connect said engaging member to said bearing member. Said bolt, besides connecting the member 63 to the shoe 64, also serves to preload a spring 84 encircling said sleeve 80, and interposed between said shoe and said engaging member 63.

The spring 84 serves to hold the engaging member 63 a fixed distance from the shoe 64 so said shoe will follow said engaging member upon downward movement of said engaging member, when said shoe is initially engaged with the ground. During this initial engaging movement of said shoe with the ground when said shoe and engaging member move together, there will be sufficient clearance between said engaging member and shoe and the sectional collar 76 so that the outward force on said sectional collar will not be sufficient to expand said collar into clamping engagement with the inside of said annular ring. Said collars therefore are free to move vertically with respect to said annular rings when initially setting the jacks 13, 13. This permits said base to be positioned to substantially conform to the plane of the shaker conveyor trough line by relative movement with respect to said collars before the shoes 64, 64 are firmly engaged with the ground by means of said jacks, as said jacks are tightened between the roof and the bearing plate 61, to initially engage said shoes with the ground. When each of said jacks is tightened further after being initially set, the engaging member 63 will move towards the partial-ball-shaped surface of the shoe 64. This movement of the frusto-conical engaging surface of said engaging member towards the spherical surface of said shoe will expand said collar to clamp the inside of said annular ring 67, and firmly hold said base in position on the ground without exerting any vertical forces thereon.

It may be seen from the foregoing that a simple and novel form of holding means has been provided for holding a swivel of a shaker conveyor trough line in position on an uneven mine floor, without exerting any forces which would tend

to bend or bind the parts of said swivel, which holding means is so arranged that when initially setting the holding jacks 13, 13 after the base 12 has been centered with respect to the stroke 5 of the conveyor, the sectional collars 76, 76 may move vertically along the inner peripheries of the annular rings 67, 67 until the respective shoes 64, 64 are in firm engagement with the ground and said base has been leveled with respect to the ground. It may further be seen that tightening of said jacks will expand said collars to grip the inner peripheries of said annular rings, and that the only forces holding said base in position are the forces of expansion of the sectional collars 76, 76 engaging the inner peripheries of the annular rings 67, 67 in planes substantially parallel to the supporting surface of the swivel base.

While I have herein shown and described one form in which my invention may be embodied, it 20 will be understood that the construction thereof and the arrangement of the various parts may be altered without departing from the spirit and scope thereof. Furthermore, I do not wish to be construed as limiting my invention to the specific embodiment illustrated, excepting as it may 25 be limited in the appended claims.

I claim as my invention:

1. In a swivel for a shaker conveyor trough line, a driving trough and a driven trough, a 30 base, means for mounting said troughs on said base for reciprocable movement with respect thereto so one may be adjusted laterally with respect to the other, holding means engageable with the mine roof and bottom, for holding said base in position on the ground, and the connection between said holding means and said base being vertically slidable when initially engaging said holding means with the ground, and gripping said base in substantially horizontal directions when said holding means have firmly been 40 engaged between the mine roof and bottom, to permit movement of said base relative to said holding means so as to relieve said base from twisting stresses and prevent distortion of said base when resting on an uneven mine bottom and held in position by said holding means.

2. In a swivel for a shaker conveyor trough line, a driving trough and a driven trough, a base, means for mounting said troughs on said base for reciprocable movement with respect thereto and permitting one trough to swing laterally with respect to the other, holding means engageable with the mine roof and bottom, for holding said base in position on the ground including a shoe engageable with the ground, a jack for engaging said shoe with the ground, and means interposed between said jack and shoe and having clamping engagement with said base, but permitting movement of said base relative to said jack upon the initial engagement of said shoe with the ground, and holding said base from movement when engaged with the ground, to hold said base in position and prevent distortion of said base when resting on an uneven mine bottom.

3. In a swivel for a shaker conveyor trough line, a driving trough and a driven trough, a base, means for mounting said troughs on said base for reciprocable movement with respect thereto and permitting one to swing laterally with respect to the other, holding means adapted to be interposed between the mine roof and bottom, for holding said base in position on the ground including a plurality of shoes engageable with the ground, a separate jack for engaging each

of said shoes with the ground, and expandible means slidably engaging said base, to permit movement thereof with respect to said engaging means after said shoes have initially come into engagement with the ground, to permit leveling movement of said base relative to said jacks upon engagement of said shoes with the ground, said means being expanded by pressure exerted by said jacks, when said shoes are being firmly engaged with the ground, to grip said base in substantially horizontal directions and prevent distortion of said base and binding of the means for mounting said troughs on said base, when said base is held in position by said jacks on an uneven mine bottom.

4. In a swivel for a shaker conveyor trough line, a driving trough and a driven trough, a base, means for mounting said troughs on said base for reciprocable movement with respect thereto and permitting one to swing laterally with respect to the other, holding means adapted to be interposed between the mine roof and the ground, for holding said base in position on the ground including a shoe engageable with the ground adjacent each side of said base, a separate jack for holding each shoe in engagement with the ground, an expandible collar interposed between each jack and shoe and forming a mounting for an associated shoe, permitting movement thereof about a plurality of axes, said collar being expanded to engage said base by downward pressure of said jack, to firmly engage said shoe with the ground, and slidably engaging said base when initially engaging said shoe with the ground by means of said jack, so as to permit leveling of said base during the initial operation of engaging said shoes with the ground, to permit said shoes to firmly engage the ground and hold said base in position where the ground is uneven, without distorting said base.

5. In a swivel for a shaker conveyor trough line, a driving trough and a driven trough, a base, means for mounting said troughs on said base for reciprocable movement with respect thereto and permitting one to swing laterally with respect to the other, holding means engageable with the mine roof and with said base for holding said base in position on the ground including a shoe engageable with the ground adjacent each side of said base, a separate jack for holding each shoe in engagement with the ground, an expandible collar interposed between each jack and shoe and forming a mounting for an associated shoe, an engaging member having inclined sides forming a seat for said jack and having engagement with said collar, for expanding said collar to frictionally engage said base upon downward movement of said associated jack, to engage said shoe with the ground, to permit slidable movement of said collar with respect to said base when initially setting said jacks and having clamping engagement with said base when said shoes are firmly engaged with the ground by means of said jacks, so said jacks may hold said base in position on an uneven mine bottom without tending to distort said base.

6. In a swivel for a shaker conveyor trough line, a driving trough and a driven trough, a base, means for mounting said troughs on said base for reciprocable movement with respect thereto and permitting one to swing laterally with respect to the other, holding means engageable with the mine roof and with said base for holding said base in position on the ground including a plurality of shoes engageable with the ground, a separate

jack for holding each shoe in engagement with the ground, an expandible collar interposed between each jack and shoe and forming a mounting for an associated shoe, a frusto-conical engaging member having engagement with said collar, to expand said collar to engage said base upon engagement of said shoe with the ground, and a connection between said engaging member and said shoe arranged to permit slidable movement of said base with respect to said collar while said shoe is initially moved into engagement with the ground by means of said associated jack, and moving said collar into clamping engagement with said base upon firm engagement of said shoe with the ground so as to permit said base to be held in position and to take distorting strains from said base and prevent bending of said base when jacked in position on an uneven mine bottom.

20 7. In a swivel for a shaker conveyor trough line, a driving trough and a driven trough, a base, means for mounting said troughs on said base for reciprocable movement with respect thereto and permitting one to swing laterally with respect to the other, holding means engageable with the mine roof and with said base for holding said base in position on the ground including a plurality of shoes engageable with the ground, a separate jack for holding each shoe in engagement with the ground, an expandible collar interposed between each jack and shoe and forming a mounting for an associated shoe, an engaging member having engagement with the inner periphery of said collar, for expanding said collar, to engage said collar with said base, and a connection between said engaging member and said associated shoe arranged to hold said collar and shoe in definite spaced relation when said shoe is being initially engaged with the ground, to permit vertical slidable movement of said collar with respect to said base and permit leveling of said base when initially engaging said shoes with the ground, and permitting said engaging member to move towards said shoe when firmly engaging said shoe with the ground, to expand said collar to have clamping engagement with said base, to hold said base from movement by the forces of expansion of said collar.

50 8. In a swivel for a shaker conveyor trough line, a driving trough and a driven trough, a base, means for mounting said troughs on said base for reciprocable movement with respect thereto and permitting one to swing laterally with respect to the other, holding means engageable with the mine roof and with said base for holding said base in position on the ground including a plurality of shoes engageable with the ground, a separate jack for holding each shoe in engagement with the ground, an expandible collar interposed between each jack and shoe and forming a mounting for an associated shoe, an engaging member having engagement with the inner periphery of said collar, for expanding said collar, to engage said collar with said base, and a connection between said engaging member and said associated shoe arranged to hold said collar and shoe in definite spaced relation when said shoe is being initially engaged with the ground, to permit vertical slidable movement of said collar with respect to said base and permit leveling of said base when initially engaging said shoes with the ground, and permitting said engaging member to move towards said shoe when firmly engaging said shoe with the ground, to expand said collar to have clamping engagement with said base, to

hold said base from movement by the lateral forces of expansion of said collar, said connection between said sleeve and shoe including a compression spring and means for preloading said spring to yield upon a predetermined pressure between said engaging member and said shoe.

9. In a holding means particularly adapted to hold a swivel base of a shaker conveyor trough line stationary during operation of the conveyor, a shoe movable vertically with respect to said base, a jack adapted to engage a mine roof and engage said shoe with the ground, and means interposed between said jack and shoe for gripping said base and holding said base from movement with respect to the ground when said shoe is firmly engaged with the ground by means of said jack, said means permitting vertical movement of said base relative to said jack when said shoe is initially engaged with the ground, to permit leveling of said base with respect to the ground, and holding said base without exerting any vertical forces thereon when said shoe is firmly engaged with the ground by said jack.

10. In a holding means particularly adapted to hold a swivel base of a shaker conveyor trough line stationary during operation of the conveyor, a shoe movable vertically with respect to said base, a jack adapted to engage a mine roof and engage said shoe with the ground, and an expandable collar interposed between said jack and shoe and expanded upon downward pressure of said jack to firmly engage said shoe with the ground, and to engage and hold said base from movement with respect to said jack when said shoe is firmly engaged with the ground, and a yieldable connection between said jack and said shoe, for slidably moving said collar with respect to said base when initially engaging said shoe with the ground and expanding said collar to firmly engage said base upon further downward pressure of said jack on said shoe, to firmly engage said shoe with the ground.

11. In a holding means particularly adapted to hold a swivel base of a shaker conveyor trough line stationary during operation of the conveyor, a shoe movable vertically with respect to said base, a jack adapted to engage a mine roof and engage said shoe with the ground, and an expandable collar interposed between said jack and shoe and expanded upon downward pressure of said jack to firmly engage said shoe with the ground, and to engage and hold said base from movement with respect to said jack when said shoe is firmly engaged with the ground, and means interposed between said jack and said shoe, for slidably moving said collar with respect to said base when initially engaging said shoe with the ground, and expanding said collar to firmly engage said base upon further downward pressure of said jack on said shoe, to firmly engage said shoe with the ground, including an engaging member adapted to expand said collar upon downward movement thereof, and a yieldable member interposed between said engaging member and said shoe, said member being adapted to yield when a predetermined pressure is exerted on said engaging member by means of said jack, to permit said engaging member to move closer to said shoe and expand said collar.

12. In a holding means particularly adapted to hold a swivel base of a shaker conveyor trough line stationary during operation of the conveyor, a shoe movable vertically with respect to said base, a jack adapted to engage a mine roof and engage said shoe with the ground, and an expand-

sible collar interposed between said jack and shoe and expanded upon downward pressure of said jack to firmly engage said shoe with the ground, and to engage and hold said base from movement with respect to said jack, when said shoe is firmly engaged with the ground, and means interposed between said jack and said shoe, for slidably moving said collar with respect to said base when initially engaging said shoe with the ground and expanding said collar to firmly engage said base, upon further downward pressure of said jack on said shoe to firmly engage said shoe with the ground, including an engaging member having a downwardly facing inclined engaging surface adapted to engage a corresponding surface on said collar to expand said collar, and means holding said engaging member a fixed distance from said shoe, to permit movement of said collar with respect to said base when said jack is initially engaging said shoe with the ground, said means being yieldable to permit said engaging member to move closer to said shoe and expand said collar, when said jack is firmly engaging said shoe with the ground.

13. In a holding means particularly adapted to hold a swivel base of a shaker conveyor trough line stationary during operation of the conveyor, a shoe movable vertically with respect to said base, a jack adapted to engage a mine roof and engage said shoe with the ground, and an expandable collar interposed between said jack and shoe and expanded upon downward pressure of said jack to firmly engage said shoe with the ground, and to engage and hold said base from movement with respect to said jack, when said shoe is firmly engaged with the ground, and means interposed between said jack and said shoe, for slidably moving said collar with respect to said base when initially engaging said shoe with the ground, and expanding said collar to firmly engage said base upon further downward pressure of said jack on said shoe to firmly engage said shoe with the ground, including an engaging member having a downwardly facing inclined engaging surface adapted to engage a corresponding surface on said collar, and a spring interposed between said engaging member and shoe for holding said engaging member and said shoe a fixed distance apart when initially setting said jack and engaging said shoe with the ground, said spring being adapted to yield when a predetermined pressure is exerted on said engaging member by said jack, to permit said engaging member to move closer to said shoe and expand said collar.

14. In a holding means particularly adapted to hold a swivel base of a shaker conveyor trough line stationary during operation of the conveyor, a shoe movable vertically with respect to said base, a jack adapted to engage a mine roof and engage said shoe with the ground, an expandable collar interposed between said jack and shoe, said collar having a downwardly opening socket adapted to form a universal pivotal mounting for said shoe, an engaging member having a downwardly facing inclined engaging surface adapted to engage a corresponding internal surface on said collar, and yieldable means interposed between said engaging member and said shoe for holding said engaging member in fixed spaced relation with respect to said shoe when said shoe is initially engaged with the ground, to permit vertical movement of said collar, with respect to said base, said yieldable means being adapted to yield upon the exertion of a predetermined pres-

11

sure on said engaging member by means of said jack, to permit said engaging member to move towards said shoe and expand said collar to grip said base.

15. In a holding means particularly adapted to hold a swivel base of a shaker conveyor trough line stationary during operation of the conveyor, a shoe movable vertically with respect to said base, a jack adapted to engage a mine roof and engage said shoe with the ground, an expandible collar interposed between said jack and shoe, said collar having a downwardly opening socket adapted to form a universal pivotal mounting for said shoe, an engaging member having a downwardly facing frusto-conical engaging surface

12

adapted to engage a corresponding internal surface on said collar, and a compression spring interposed between said engaging member and said shoe for holding said engaging member in fixed spaced relation with respect to said shoe when said shoe is initially engaged with the ground, to permit vertical movement of said collar with respect to said base, said spring being adapted to yield upon the exertion of a predetermined pressure on said engaging member by means of said jack, to permit said engaging member to move towards said shoe and expand said collar to grip said base.
